UNITED STATES PATENT OFFICE

161,369

COVERING FOR SMOOTH SURFACES

William B. Petzold, Pittsfield, Mass., assignor to
General Electric Company, a corporation of
New York

Application October 26, 1946, Serial No. 134,277

Term of patent 14 years

(Cl. D59—10)

To all whom it may concern:

Be it known that I, William B. Petzold, a citizen of the United States, residing at Pittsfield, in the county of Berkshire, Commonwealth of Massachusetts, have invented a new, original, and ornamental Design for a Covering for Smooth Surfaces, of which the following is a specification, reference being had to the accompanying drawing, forming a part thereof.

Figs. 1a-1d, taken together and joined at lines A—A, B—B, and C—C, is a plan view of a covering for smooth surfaces, showing my new design. A complete design unit is shown reduced about one-half and enclosed between lines D—D and E—E. Fig. 2 is a full scale plan view of the portion of the design unit outlined in broken lines on Fig. 1d, and Fig. 3 is a cross-sectional view of Fig. 2 in the direction 3—3.

I claim:

The ornamental design for a covering for smooth surfaces, as shown and described.

WILLIAM B. PETZOLD.
